UNITED STATES PATENT OFFICE.

JAMES H. NORTHROP, OF HOPEDALE, MASSACHUSETTS, ASSIGNOR OF ONE-HALF TO GEORGE DRAPER & SON, OF SAME PLACE.

KNOT-TYING APPARATUS FOR SPOOLING-MACHINES, &c.

SPECIFICATION forming part of Letters Patent No. 325,624, dated September 1, 1885.

Application filed November 5, 1883. (Model.)

To all whom it may concern:

Be it known that I, JAMES H. NORTHROP, of Hopedale, county of Worcester, State of Massachusetts, have invented an Improvement in Knot-Tying Apparatus for Spooling-Machines, &c., of which the following description, in connection with the accompanying drawings, is a specification, like letters on the drawings representing like parts.

10 This invention has for its object the production of a novel knot-tying apparatus adapted to tie knots in yarn or thread, twine, &c., and cut the same off near the knot, the said apparatus being, among other uses, adapted to tie ends in spooling-machines, or to tie the cords or strings in reaping and binding machines.

In this invention a case or sleeve, forked at its free end, cut through at one side, and provided internally with a screw-thread, receives 20 in it a screw-threaded spindle, which has attached to it at one end a blade composed of two spring-arms, and the shank of the spindle is extended loosely through and has splined to it a pinion, rotation of which, by toothed 25 gearing outside the sleeve, effects the rotation of the spindle and attached blade to tie a knot in the yarns or threads held between the spring members of the blade, the said yarns or threads to be tied being held each side the path of rotation of the forked part of the blade, the latter co-operating with a part of the sleeve to sever or cut off the yarn or thread close to the knot.

30 My invention consists, essentially, in a case or sleeve slotted at its end to receive the threads to be acted upon, and provided with a screw-thread and a screw-threaded spindle, a blade, and a pinion, combined with a sector to engage the said pinion and rotate and reciprocate the spindle and blade, as will be described.

Figure 1 in side elevation represents a knot-tying device embodying my invention, the same being shown as adapted for use in connection with a spooling-machine. Fig. 2 is a 40 front view of the device shown in Fig. 1. Fig. 3 is a section on the line $x-x$, Fig. 1, the spindle, its attached parts, and the screw to pivot the sleeve on the standard being shown in elevation. Fig. 4 is an inner side view of the

upper end of the case or sleeve. Fig. 5 is a 50 bottom view of the case or sleeve and the parts within it, the said figure showing two threads or cords placed in the slots of the case to be tied. Fig. 6 is a detail of part of the case or sleeve and the fork, the latter occupying the 55 same position with relation to the threads or cords as in Fig. 5. Figs. 7 and 8 represent views similar to Figs. 5 and 6, but with the fork in a different position, a part of the case next the front of the blade in Fig. 7 being broken out, to better show the position of the thread or cord. Figs. 9 and 10 and Figs. 11 and 12 are other views similar to Figs. 7 and 8, but showing the fork in different positions and the knot in different steps of completion. 65 Fig. 13 represents the kind of knot which will be laid in the threads or cords.

The standard A has at its upper end a screw, A', which receives the hub a near the upper end of the case or sleeve B, the said screw forming a fulcrum for the said case or sleeve. The hub receives about it a spiral spring, a', the ends a² a³ of which are held, respectively, by the standard and case, the tendency of the spring being to hold the case normally in the 75 position Fig. 1. The case or sleeve is provided at its lower end with two slots, 2 3, for the reception of the yarn, thread, or cords 4 5, which are to be tied in a knot such as shown in Fig. 13.

80 The case is provided with a finger or pull piece, b, and with a stop, b', is cut away at two sides, as shown at b² and b³, and is provided centrally with a screw-thread, b⁴, to receive the screw-threaded shank c of the spindle c', provided with a pinion, c², which is engaged by a toothed sector, c³, connected at one end with the standard or support A, and at its other with the arm c⁴, attached to the said standard.

85 The lower end of the spindle has attached to it the fork D, composed of thin blades d' d², shaped substantially as shown in the drawings, the end of one overlapping the other to form a crotch to receive the threads or cords 90 between them when the knot has been almost completed, as in Fig. 10, in order that the said threads or cords drawn into the crotch or space

between the blades, when brought by the further revolution of the spindle against the corner 8 of the case, produced by making the slot 3, will be severed or broken off close to the 5 base of the crotch between the said blades and close to the knot, so that the threads or cords held in the left hand of the operator, and shown at the left in Fig. 12, may be drawn from the fork, passing off the ends of the blades, forming 10 a knot such as shown in Fig. 13, which is, however, drawn close, for the blades at the base of the crotch hold the two ends at the right of the knot while the threads are being drawn off the blades. The knot having been 15 drawn close, further strain on the threads in the same direction overcomes the holding-power of the blades, and the threads with their ends tied are fully detached from the knot-tying device.

20 The fork D is attached to the spindle by the screw h .

The movement of the case or sleeve toward the junction of the sector c' with the standard under the action of the spring a' is arrested by the stop b' striking against the shoulder h^2 of the standard or support.

I claim—

1. The case or sleeve B, slotted at its end to receive the material to be tied, and provided with a screw-thread, a standard or support for the sleeve, the screw-threaded spindle and its attached blade D, and the pinion on the spindle, combined with a toothed segment to engage and rotate the said pinion, and with it the spindle, substantially as described. 30

2. The case or sleeve B, slotted at its end at 2 3, cut through at its side, and provided with a screw-thread and with a projection, b , and the screw-threaded spindle, its attached forked blade, composed of two spring plates or portions, d' d^2 , and the pinion c' , combined with the standard or support, the pivot-pin, and the rack to rotate the pinion and spindle, to 40 operate substantially as described.

In testimony whereof I have signed my name 45 to this specification in the presence of two subscribing witnesses.

JAMES H. NORTHROP.
